UNITED STATES PATENT OFFICE.

ADAM MANCHESTER, OF CENTRAL BRIDGE, NEW YORK.

COMBUSTION-ENGINE-SPARK-PLUG PROTECTOR.

Application filed December 30, 1925. Serial No. 78,372.

This invention relates to protectors for spark plugs and has more particular reference to a means for engagement over the projecting ends of spark plugs for preventing the accumulation of dirt, moisture and the like within the usual pockets that are formed in certain types of motors that surround the plugs.

It will thus be seen that the primary object of the invention is to provide a means for preventing the accumulation of dirt or moisture into said pockets which would otherwise result in the short circuiting or otherwise impairing the proper operation of the plugs in the motor.

A further and important object is to provide a protector plate of this character that may be readily employed in conjunction with a number of well known motors and that may be readily applied or removed as the occasion demands.

With the foregoing and other objects in view as the nature of the invention will be better understood, the same comprises the novel form, combination and arrangement of parts hereinafter more fully described and shown in the accompanying drawing and claimed.

In the drawing wherein like reference characters indicate corresponding parts throughout the several views:—

Figure 1 is a top plan view of the protector plate as actually applied to a motor of conventional design,

Fig. 2 is a fragmentary section through said motor and plate for more clearly disclosing the relationship of a spark plug with respect to the plate,

Fig. 3 is a bottom plane view of the plate, per se, and

Fig. 4 is a fragmentary vertical section through a portion of one of the cylinder head securing bolts and plate for clearly disclosing the means whereby the plate is rigidly secured to the cylinder head.

In the drawing, there is disclosed fragmentarily a conventional cylinder head that is provided with one or more pairs of closely related spark plug openings surrounding each of which is the well known pocket 5 for reducing the thickness of the head at the points provided with a spark plug receiving opening 6. Thusly, the protector plate disclosed in the present invention is of such construction as to permit of the pair of closely related pockets to be covered simul-

taneously and also for permitting of the attachment of the usual ignition circuit wires to the plugs within the openings surrounded by said pockets.

With particular reference to the drawing, my invention constitutes the provision of a metallic plate 7 that is so formed as to provide a pair of interconnected relatively circular-shaped portions 8—8, the rear sides 65 thereof merging into a straight edge 9 in order that the plate may be maintained at this edge in flush engagement with the relatively vertical portion *a* of the motor head A. The curved edges of the portions 8—8 70 comprising said plate 7, are turned downwardly as at 10 in order that the plate may be supported in a horizontal manner upon the cylinder head as more clearly shown in Fig. 2. Said downwardly turned portion as 75 well as the rear plane edge 9 of the plate is channeled for receiving a packing strip 11 for preventing the passage of moisture between the plate and the cylinder head and consequently reaching the pockets 5 over 80 which are disposed the circular portions 8—8 of said plate.

Each circular portion 8 of the plate 7 is formed centrally with a circular opening 12 within which is arranged a cap 13 of insulating material, the top wall of which is in turn formed with an opening 14 for permitting of the upper end of the spark plug B projecting therethrough in order that the usual ignition wire may be secured thereto. 90

The cap and its means of attachment is preferably of the construction as shown in the sectional view, Fig. 2. However, I do not wish to be limited such a construction as departures may be had therefrom without 95 effecting the spirit and scope of the appended claims.

In motors of the character disclosed, the head A is secured to the block through the medium of stud bolts, one of which is usually 100 positioned intermediate the adjacent pockets 5 at the rear side thereof, this stud bolt being designated in the drawing C.

In this instance the head of the bolt upon the top side of the motor vehicle A is formed 105 with a threaded socket 15 within which is threaded the enlarged threaded end 16 of a small threaded bolt 17 that is adapted to extend through an opening 18 in the plate 7 when the same is disposed upon the motor 110 head in a manner as shown in Figs. 1 and 2. After the plate has been so positioned, a

wing nut 19 is to be threaded upon said bolt 17 for maintaining the plate in firm engagement upon the head of the motor.

It will thus be seen that I have provided 5 a highly novel, simple and efficient form of protecting plate for the spark plugs of combustion engines that will effectively prevent the accumulation of dirt or moisture into the pockets that surround the plugs in conventional types of motors.

10 I do not desire to be limited to the specific structural elements such and described in so much as in the future practice of the invention, modifications may be made without affecting the spirit and scope of the appended 15 claims.

Having thus described my invention, what I claim as new and desire to secure by Letters Patent is:—

20 1. In a protector for internal combustion engine spark plugs wherein the engine is formed with pairs of closely related spark plug openings surrounding which are plug wrench receiving pockets, of a plate member 25 formed of a plurality of circular portions adapted to be disposed over said pockets, each of said circular portions being provided with an opening for permitting the upper end of the spark plug to be projected 30 therethrough, a cap formed of insulated material arranged in each of said openings, the top of each cap having an opening provided therein through which the upper end of the spark plug extends, and means for securing 35 the plate on the engine.

2. In a protector for internal combustion engine spark plugs wherein the motor head is formed with pairs of closely related spark plug openings, and surrounding which are 40 plug wrench receiving pockets, a plate member including a plurality of circular portions adapted to be disposed over the respective pockets, said circular portions having openings for permitting the upper portion 45 of a spark plug to project therethrough, the peripheral edge of the plate having a channel formed therein, a packing strip arranged in the channel and adapted to engage the motor head to provide a dustproof joint, 50 and means for securing the plate on the motor head.

3. In a protector for internal combustion

engine spark plugs wherein the motor head 55 is formed with pairs of closely related spark plug openings, and surrounding which are plug wrench receiving pockets, wherein a substantially vertical wall rises from the rear portions of the pockets, a plate member 60 formed of a plurality of circular portions adapted to be disposed over the respective pockets, said circular portions having openings for permitting the upper portion 65 of a spark plug to project therethrough, a horizontal straight edge at the rear side of the plate for contact with said vertically extending rear wall of the motor head, the front and side edges of the plate being disposed 70 downwardly for engagement with the horizontal top portion of the head, the peripheral edge of the plate having a channel formed therein, a packing strip arranged in 75 said channel to provide a dustproof joint between the plate and the motor head, and means for securing the plate on said head.

4. In a protector for internal combustion engine spark plugs wherein a motor head is formed with pairs of closely related spark 80 plug openings, and surrounding which are plug wrench receiving pockets, wherein a substantially vertical wall rises from the rear portions of the pockets, a plate member 85 formed of a plurality of circular portions adapted to be disposed over the respective pockets, said circular portions having openings for permitting the upper portions of a spark plug to project therethrough, a horizontal straight edge at the rear side of the 90 plate for contact with said vertically extending rear wall of the motor head, the front and sides of the plate being disposed downwardly for engagement with the horizontal top portion of the head, the peripheral 95 edge of the plate having a channel therein, a packing strip arranged in said channel to provide a dustproof joint between the plate and the motor head, a cap of insulated material secured in each of said openings, the 100 top of each cap having an opening formed therein through which the upper end of the respective spark plug extends, and means for securing the plate on the motor head.

In testimony whereof I affix my signature.

ADAM MANCHESTER.
